RETRACTABLE LANDING GEAR FOR AERO-
PLANESRené Lucien Lévy, Montrouge, France, assignor
to Société d'Inventions Aéronautiques et
Mécaniques, S. I. A. M., Fribourg, SwitzerlandApplication January 9, 1936, Serial No. 58,397
In France February 4, 1935

1 Claim. (Cl. 244—102)

It is known that, in some forms of retractable landing gear for aeroplanes completely to withdraw each wheel into a housing in a wing such that, in order to reach the housing, the wheel, in being raised from its lowered position, has to describe a movement towards the rear—or towards the front,—sometimes even in an oblique direction in relation to the median plane of the aeroplane.

Known solutions—the application of which, however, is far from being satisfactory in all the cases on account of the diversity of structure of the numerous types of aeroplanes—consist in displacing the wheel either about an obliquely directed axis, or about two axes. In the latter case, the raising is effected in two successive stages, for example, at first by a rotational movement towards the rear, and then by a lateral rotation—and vice versa for lowering.

The object of the present invention is a retractable wheel assembly in which the wheel describes two rotational movements about two distinct axes, but is characterized substantially—by comparison with the above mentioned systems—in that the two rotations are combined and proceed simultaneously, the resultant movement being determined entirely by the presence of a member—bar or the like, of constant length, which maintains a continuous connection between a fixed point on the aeroplane and a suitably selected point on the leg, or similar mobile member, supporting the wheel.

In the accompanying drawings, Figures 1 to 3 and Figures 4 to 6 represent respectively two embodiments of such retractable gear according to the present invention, Figure 1 being a front elevation of a first embodiment, Figure 2 being a corresponding plan and Figure 3 a side elevation thereof, whilst Figure 4 is a front elevation of a second embodiment, Figure 5 a plan thereof, showing the wheel in the retracted position, and Figure 6 a side elevation showing the wheel in the lowered position.

Referring to Figures 1-3; the wheel R is carried by a cushioning leg J, constituted for example, in the form of an oleopneumatic shock absorber.

The upper part of the leg J is bifurcated as at p and pivoted on the aeroplane by a spindle a a carried, in turn, by a rod b b the axis of which, in this example, is perpendicular to that of the former.

The path of the wheel in passing from the lowered position R to the retracted position R', is determined completely by the presence of a bar K, of constant length, pivotally mounted on the one hand, at a fixed point c—which, in the example shown, is on one of the longérons of the wing—and, on the other hand, at a point g

on the supporting leg J. The joints c and g which should possess at least two degrees of freedom, will be in the form for example, of ball joints.

The actuating members for raising or lowering the gear may—if the relative arrangement of the several members of the articulated system permits—be combined in a single jack of the double-acting type, that is one which works in both directions.

As in the typical case selected, there may also be provided, for lowering the gear, a single acting jack V, pivotally mounted, on the one hand, on the axis of the rod, b b and, on the other, at a point e on the leg J. The raising is effected by a second jack T, pivoted on a fixed point k and acting on the end of a crank m, keyed on the rod b b. In the position T', said jack T also serves to maintain the wheel in the raised position R'.

In the figures, the reference characters showing the position of the various members when raised, are distinguished by the index 1. Moreover, for the sake of clarity, certain members are represented solely by their axial line.

Figures 4 to 6 represent another embodiment of the invention. They relate to an example in which the shock absorber A, mounted on the wheel R, forms part of a pivotal triangular support A—J—B (Figure 6). The leg J—on which the link B and shock absorber A are pivoted at d and f respectively—is the equivalent of the member J in the previous example. The members described in relation to this latter are shown—with the same reference characters—in Figures 4 to 6, and particularly the bar K, of constant length, which determines the path of the leg J, movable about two axes a—a and b—b, that is to say, the characteristic combination of the invention.

What I claim as my invention and desire to secure by Letters Patent is:—

Retractable landing gear for aeroplanes, comprising, a wheel, a first element constituted by a leg supporting the wheel, two separate axes intersecting at a fixed point and around which the supporting leg is adapted to pivot, a second element constituted by a directing bar of constant length connected to a fixed point of the aeroplane and to a point of the supporting leg, a third element constituted by a jack pivoted on the one hand at a point on one of the oscillating axes of the supporting leg and on the other hand at a point of the said leg, a second jack pivoted on the one hand at a fixed point of the aeroplane and on the other hand on a crank keyed on the said oscillating axis.

RENÉ LUCIEN LÉVY.
